TYPEWRITING MACHINE

William A. Dobson, Bridgeport, Conn., assignor to Underwood Elliott Fisher Company, New York, N. Y., a corporation of Delaware

Application July 6, 1931. Serial No. 548,863

12 Claims. (Cl. 197—123)

This invention relates to platen-release mechanism of typewriting machines.

An object of the invention is to provide a mechanism easy to assemble, dismount, clean or 5 repair, compact, light, durable and cheap, for portable typewriters.

The usual carrying case is placed over the entire typewriter, thereby limiting the length of the typewriter-carriage, and precluding the 10 use of the well-known platen-releases, since they extend considerably beyond the ends of the carriage.

In the present invention, substantially the entire mechanism is compactly housed within the 15 platen. The line-space wheel and its related parts retain their old positions, and the typewriter-carriage does not have to be lengthened.

A thimble-cam is made fast to an axially-slidable platen-shaft, and spreads a pair of rigid 20 pivoted clutch-levers, which are mounted in the platen, said levers normally exerting toward one side of the loose line-space wheel a lateral pressure to bind it between two clamping jaws (connected to the platen) with sufficient force for 25 positively clutching the platen to said wheel.

A very fine adjustment of the clutching force required to couple the platen to the ratchet-wheel is obtained by simply displacing axially the fixed 30 jaw of the clamp.

Said adjustment is preferably obtained by providing the projecting hub of the carrier with a 35 thread, and the fixed jaw of the clamp is made in the form of a disk which forms a flange upon a nut, which is threaded upon said hub. A lock-nut may be used to fix said fixed jaw in the 40 desired position.

The movable jaw of said clamp is a relatively thin washer, rotating with the platen, but with a 45 certain extent of axial play, and the pressure applied by the clutch-levers may be uniformly distributed through said washer upon a relatively large surface of friction.

Jarring of the platen during case-shifting and 50 carriage-return movements cannot accidentally release it, the clutch being constantly maintained in closed condition by the forcing action of the clutch-levers and cam.

The platen of the Underwood portable typewriter needs to be lengthened but little, if any, 55 and no change is needed in the typewriter-carriage. In the clutching and unclutching operations no part of the mechanism rubs against the line-space wheel, and the action of the clutching organs is most effectively directed, inasmuch

as there is exerted a direct lateral pressure over a large area of wheel-surface.

There does not need to be a single spring or resilient part.

The left-hand carriage-end-plate of the portable Underwood typewriter is provided with a lengthened internal hub, insuring a perfect centering and support of the platen and line-space wheel, as the left-hand hub of the platen bears upon the inner end of said hub. The latter 60 also affords a long bearing for the shaft.

Other features and advantages will hereinafter appear.

In the accompanying drawing,

Figure 1 is an axial section of a platen and 70 its appurtenances, with the clamping device in release position.

Figure 2 is similar to Figure 1, but shows the clamping device closed.

Figure 3 is an end view with parts taken away 75 for clearness.

Figure 4 is a perspective view of the invention, with parts disassembled.

Figure 5 is another perspective view with parts 80 broken away for clearness.

A platen 10 is rotatably supported by means of right and left hand platen-shafts 11 and 12, mounted in carriage-end plates 13. The right-hand platen-shaft 11 has a knob 14 fixed by set-screw 15. This shaft is comparatively short, and 85 extends inwardly through a hub 16 on the carriage-end plate 13 and into a hub 17 that forms part of the right-hand end-wall 18 of the platen, rigidly attached by screws 19. A set-screw 20 fixes shaft 11 to the hub 17.

The left-hand platen-shaft 12 is slidably mounted within the platen, and is supported at its inner end in an extension 21 of hub 17. The outer end of the shaft 12 has a bearing in a centering hollow journal 22 on the carriage-end plate 95 13 and carries at its extreme end a knob 23 rigidly attached by a screw 24. The inner end of the shaft 12 is provided with flattened sides 25 to fit in a key-way 26 in the extension 21.

The knob 23 is thus connected to either rotate 100 the extension 21, together with the platen 10, or to move the shaft 12 endwise to operate a platen-release mechanism, as will be described later.

A line-space wheel 27, loosely mounted at the left-hand side of the platen, is normally clutched 105 to said platen 10 by means of a novel mechanism, which includes a thimble-cam 28 retained by a pin 29 on the platen-shaft 12 at a place within an opening 30 of a platen-core 31. The cam 28 when moved to effective position engages 110

the inner ends 32 of long arms 33 of a pair of clutch-operating rigid levers 34. These levers are lodged within a metal shell 35, fitting in the opening 30 and rigidly attached to the platen-core 31 by screws 36, and are pivoted at 37 in slots 38 provided in the end wall 39 of the platen. Said end wall 39, which thus constitutes a carrier for the clutch-levers 34, is fixed by screws 40 within said shell at the end of the platen, and has a central hub 41 with a threaded extension 42. To allow the axial displacement of the shaft 12, the bore 43 of said hub 41 has a diameter slightly larger than the cam 28. The extension 42 bears upon the periphery of the hollow journal 22, so as to insure a perfect parallelism between the platen and its two shafts, a clearance 44 being provided in that bearing in order to allow a slight tilting of the platen about said journal 22, when, for repair or inspection, it is desired to remove the platen. Said removal may be made by first removing the shaft 11 and the knob 23, pushing the shaft 12 beyond the hollow journal 22, and then tilting the whole platen until it may be disengaged from the journal 22.

25 A nut 45 with a flange 46, provided with key-holes 47, may be adjustably fixed in position on the threaded extension 42 by means of a lock-nut 48. The ratchet-line-space wheel 27 is loosely mounted on said nut 45 and is normally clamped between said flange 46, constituting the fixed jaw of a clamp, and a washer 49 acting as the movable jaw of said clamp. Said washer is angularly coupled to the end wall 39 by means of guide-pins 50 screwed in the outer side of said wall 39 and fitting in corresponding holes 51 of the washer 49, but is free to slide axially along said pins 50 between the end wall 39 and the ratchet-wheel 27.

40 The short arms 52 of the levers 34, when the cam 28 spreads the long arms 33 of the same, act as a self-releasing wedge, and press upon said washer 49, so as to operate the clamping of the ratchet-wheel 27 between the flange 46 and said washer 49. The shape and ratio of leverages of the levers 34 are such that a very strong clamping action may be obtained by very smooth and easy pushing-in of the knob 23.

45 The short arms 52, when the levers 34 are released, just touch said washer 49 and thus allow the platen to rotate freely, while the line-space wheel 27 is held stationary by means of its usual spring-detent roller 53. The point of contact of each short arm 52 is sufficiently outside of the pivot-center of lever 34 when the line-space wheel 55 is clamped, to insure self-releasing movement of said lever when the cam 28 is withdrawn.

50 To connect the line-space wheel to the platen, the knob 23, together with the shaft 12 and cam 28, is pushed endwise towards the right until the knob abuts against the end plate 13 (Figure 2). This forces the cam 28 between the levers 34, the long arms of which are then spread in the direction of the arrows, while their short arms 52 act as self-releasing wedges, so as to close the clamp 46, 49, thereby clutching the platen rigidly to the line-space wheel.

55 When it is desired to disconnect the platen from the line-space wheel, the knob 23 is pulled out to the left until the left-hand end of the cam 28 abuts the journal 22 (Figure 1). In this position the cam 28 is fully withdrawn from the ends of the long arms 33 of the levers 34, allowing them to rotate about their pivots 37 back to their idle 70 position, and thereby open the clamp 46, 49, thus

disconnecting the platen from the ratchet-wheel 27.

It will be noticed that when the levers 34 are rotated in the direction of the arrows (Figure 2), a clamping or clutching force is applied directly 80 at two diametrically-opposed middle points on the washer 49. The very strong and well distributed friction may thus be laterally applied over a relatively large surface of the ratchet-wheel 27 by means of a very short axial displacement of the washer 49.

85 In assembling the platen-release mechanism of the present invention, the levers 34 with their pivots 37 and the guide-pins 50 are first mounted on the carrier 39. The flanged nut 46, carrying the ratchet-wheel 27 and the washer 49, and the lock-nut 48 are then loosely screwed on the threaded extension 42. The washer 49 has two holes 51 which engage the guide-pins 50.

90 The compact whole thus formed is inserted in the metal shell 35 and secured thereto by the screws 40. The shell is fixed to the platen-core 31 by means of the screws 36. The shaft 12, together with its cam 28, is introduced within the hub 41 and said core 31, and the flattened end 100 of the shaft 12 is inserted in the key-way 26. The left-hand end of the platen is now first engaged on the centering journal 22, the clearance 44 of the extension 42 facilitating this operation, and the right-hand end brought against the hub 105 16. The shaft 11, carrying the knob 14, is introduced through said hub 16 into the hub 17 and fixed in position by means of the set-screw 15. The shaft 12 is thus pushed leftward through the journal 22, so that its left-hand end 110 projects beyond the end plate 13. Knob 23 may now be fixed to said end by its set-screw 24. The whole platen-release mechanism is now mounted in position on the typewriter-carriage and is ready to be adjusted so as to correct any 115 excess or insufficiency of the clamping force obtained when the shaft 12 is shifted in the position shown on Figure 2.

120 This adjustment is made with the help of a suitable spanner-key fitting the notches 47. By turning the flanged nut 45, 46, different trial positions, there may be determined a position which gives at the same time a clamping or clutching action sufficient for positively coupling the platen to the ratchet-wheel 27 and a smooth 125 easy shifting in and out of the shaft 12. When that is done, the nut 45 is secured in this adjusted position with the lock-nut 48.

130 It will be noticed that as, in their operative position, the levers 34 press rigidly at the same time on the ratchet-wheel 27, through washer 49, and upon the periphery of the cam 28, the clamp 46, 49 is positively prevented from becoming accidentally disconnected by the jarring of the platen during carriage-returning and case-shift 135 movements.

140 The cam 28 is tapered on its right-hand side in order to give a progressive spreading of the levers 34 when the shaft 12 is pushed in and is also symmetrically tapered on its left-hand side 145 so as to facilitate the introduction of the shaft 12 between the ends of the long arms 33 of the levers 34 and within the hub 41 during the assembling.

150 Variations may be resorted to within the scope of the invention, and portions of the improvements may be used without others.

Having thus described my invention, I claim:

1. In a typewriting machine, in combination, a platen, a clamp carried at one end of said platen,

- a slideable shaft coupled to said platen, a line-space wheel loosely mounted within said clamp, releasable means controlled by the axial displacement of said shaft for applying a clamping force upon said wheel, means for distributing said clamping force uniformly over a relatively large annular surface of friction on both sides of said wheel, and means for adjusting said clamping force from the exterior of said platen without any dismounting being required therefor.
2. In a typewriting machine, a platen, side walls closing both ends of said platen, a central projection integral with one of said side walls, a flanged ring constituting the fixed member of a clutch adjustable and lockable on said projection, a washer constituting the movable member of said clutch slidably mounted on said ring and coupled to the adjoining side wall, a line-space wheel loosely mounted on said ring between the flange thereof and said washer, a slideable shaft angularly coupled to said platen, rigid clutch-operating levers pivoted to the side wall carrying said projection, and means on said shaft to control said clutch through said levers by axial displacement of said shaft.
3. In a typewriting machine, a platen, a hub with a threaded projection fixed at one end of said platen, a flanged nut screwable and lockable on said projection, a lock-nut to fix said flanged nut in an adjustable position, a line-space flat wheel loosely mounted on said nut and abutting the flange thereof, a springless clutch normally applying a lateral pressure on the opposite face of said wheel so as to positively couple the platen to said wheel, the amount of said pressure depending on the position of said flanged nut on said projection, a slideable shaft coupled to said platen, and means fixed on said shaft to control said clutch by the axial displacement of said shaft.
4. In a platen-release mechanism for portable typewriters, a platen, a line-space ratchet-wheel loosely and independently mounted at the left-hand end of said platen, an abutment adjustably secured to said platen on the outer side of said wheel, a pair of diametrically-opposed pivoted rigid levers to apply a clutching pressure on the opposite side of said wheel, a slideable washer coupled to said platen and interposed between said wheel and said levers, so as to distribute uniformly said clutching pressure over a relatively large annular surface of said wheel, a slideable shaft coupled to said platen, a manually-operated cam carried on said shaft for controlling said levers, and means carried by the left-hand end plate of the carriage of the typewriter for centering said platen and its related parts with respect to said shaft.
5. In a typewriting machine, a platen provided at one end with a cylindrical opening, a shell secured to said platen and fitting within said opening, a slotted end-wall internally fixed to said shell, a hub with a lateral threaded extension integral with said end-wall, a nut screwable on said extension, so as to form the fixed wall of a groove of variable width, an axially-movable washer coupled to said slotted end-wall and forming the movable wall of said groove, a thin toothed washer serving as line-space wheel loosely mounted in said groove, a cam-shaft angularly coupled to the platen and axially movable within said hub, a cam secured to said shaft and releasable rigid instrumentalities actuated by the axial displacement of said cam-shaft for normally squeezing said line-space wheel between the fixed and movable walls of said groove, so as to positively couple by friction the platen to said wheel.
6. In a typewriting machine, a platen provided at one end with a cylindrical opening, a shell secured to said platen and fitting within said opening, a slotted end-wall internally fixed to said shell, a hub with a lateral threaded extension integral with said end-wall, a nut screwable on said extension and shaped so as to form the fixed wall of a groove of variable width, an axially-movable washer coupled to said slotted end-wall and forming the movable wall of said groove, a thin toothed washer serving as line-space wheel loosely mounted in said groove, a shaft angularly coupled to the platen and axially movable within said hub, a cam secured to said shaft, and releasable rigid clutch-levers pivoted within the slots of said end-wall and normally pressing on said movable wall, so as to squeeze the line-space wheel within said groove and thus positively couple by friction the platen to said wheel.
7. In a typewriting machine, a platen provided at one end with a cylindrical opening, a shell secured to said platen and fitting within said opening, a slotted end-wall internally fixed to said shell, a hub with a lateral threaded extension integral with said end-wall, a nut screwable on said extension and shaped so as to form the fixed wall of a groove of variable width, an axially-movable washer coupled to said slotted end-wall and forming the movable wall of said groove, a thin toothed washer serving as line-space wheel loosely mounted in said groove, a shaft angularly coupled to the platen and axially movable within said hub, a cam secured to said shaft, and a pair of diametrically-opposed releasable rigid clutch-levers pivoted within the slots of said end-wall, each of said levers comprising a long hooked arm working in the interior of the opening of the platen and co-operating with said cam and a short arm acting as a wedge on said movable wall, so as to vary the width of said groove according to the position of said cam and normally squeeze the line-space wheel within said groove.
8. In a typewriting machine, a platen provided at one end with a cylindrical opening, a shell secured to said platen and fitting within said opening, a slotted end-wall internally fixed to said shell, a hub with a lateral threaded extension integral with said end-wall, a nut screwable on said extension and shaped so as to form the fixed wall of a groove of variable width, an axially-movable washer coupled to said slotted end-wall and forming the movable wall of said groove, a thin toothed washer serving as line-space wheel loosely mounted in said groove, a shaft angularly coupled to the platen and axially movable within said hub, a cam secured to said shaft, a pair of diametrically-opposed releasable rigid clutch-levers having normally their long hooked arms spread apart by said cam and their short arms pressing on said movable wall, so as to couple by friction the platen to said line-space wheel, and means for adjusting said pressure, readily accessible from the exterior without any dismounting being required therefor.
9. In a typewriting machine, a platen, a clamping device carried on the left-hand side of said platen, an independent line-space wheel loosely mounted within said clamping device, a slideable shaft coupled to said platen and carrying only an operating knob and a cam for controlling said clamping device, and a centering hub carried by the left-hand end-plate of the typewriter-carriage, said knob co-operating with the outer side

- of said hub to limit the pushing-in of said shaft, while said cam co-operates with the inner side of said hub to limit the pulling-out of said shaft
10. In a typewriting machine, the combination 5 with a revoluble platen and a loose line-space wheel, of a head within the platen and fixed thereto, fixed and loose jaws upon said head for clamping said wheel, opposed levers mounted upon said head within the platen and bearing 10 against one of said jaws to clamp said line-space wheel against the other jaw, a platen-shaft having a knob on its outer end and provided with a cam on its inner end to force said levers to close the clamping jaws and hold them closed during 15 the normal operation of the machine, said head having a central opening through which said shaft extends, said fixed jaw being screw-threaded upon said head for fine adjustment of the fixed jaw to regulate the pressure of the clamp, 20 and means for locking the fixed jaw where adjusted.
11. In a typewriting machine, a platen-release mechanism including, in combination, a platen, a line-space wheel adjacent one end of said platen, a clamping device having a fixed jaw on the outer side of said wheel and a releasable jaw on the inner side, means fastened to said platen and forming a mounting for said jaws and wheel, said mounting means and fixed jaw being arranged for relative adjustment without dismantling the mechanism, said releasable jaw being keyed to said mounting means to prevent relative rotation while permitting clamping movement thereof, a platen-rotating shaft extending 35 through said mounting means, coupled to said platen for endwise movement and having a cam thereon disposed within said platen, and a clamp-lever device pivoted to said mounting means within said platen, for actuation by said cam to press the releasable jaw toward the fixed jaw, and thereby couple the line-space wheel, between said jaws, to said platen or to release said wheel upon endwise movement of said shaft.
12. In a typewriting machine having a carriage with platen-supporting ends, the combination 35 with the revoluble platen, of a line-space wheel between one platen-end and one of said carriage-ends, a clamping device for releasably coupling said wheel and platen, said device including a body-member fastened at said one platen-end and projecting beyond the same to carry said line-space wheel and clamping device, a platen-rotating shaft slidably coupled to said platen at a point between said device and the other platen-end, said clamping device and shaft being arranged for operation of said device by endwise shaft-movement, said body-member having a central opening substantially larger than said shaft for admitting the latter, said shaft extending outside of said one carriage-end to carry a platen-knob, said one carriage-end having a hollow journal fitting said opening to form a platen-end bearing about which the platen may be slightly cocked, and means journaling the other platen-end in the other platen-supporting carriage-end, said latter journaling means being retractile to permit withdrawal of said platen from said carriage.
